DESIGN FOR AN EMBROIDERED MONOGRAMMED MEDALLION

Elmer P. Goldsmith, New York, N. Y.

Application February 2, 1946, Serial No. 126,192

Term of patent 3½ years

(Cl. D3—9)

To all whom it may concern:

Be it known that I, Elmer P. Goldsmith, a citizen of the United States of America, residing in New York, county of New York, and State of New York, have invented a new, original, and ornamental Design for an Embroidered Monogrammed Medallion, of which the following is a specification, reference being had to the accompanying drawing, forming part thereof, wherein the fig-

ure is a front elevational view of an embroidered monogrammed medallion showing my new design.

The embroidered monogrammed medallion has no appreciable thickness.

I claim:

The ornamental design for an embroidered monogrammed medallion, substantially as shown and described.

ELMER P. GOLDSMITH.
